UNITED STATES PATENT OFFICE.

LEWIS GIBBS, OF CANTON, OHIO.

DESIGN FOR AN EMBROIDERY-HOOP.

SPECIFICATION forming part of Design No. 28,671, dated May 17, 1898.

Application filed March 21, 1898. Serial No. 674,682. Term of patent 14 years.

To all whom it may concern:

Be it known that I, LEWIS GIBBS, a citizen of the United States, residing at Canton, in the county of Stark and State of Ohio, have invented a new and useful Design for Embroidery-Hoops, of which the following is a specification.

My invention relates to a new and useful design for an embroidery-hoop; and it consists of a hoop of the configuration and ornamentation shown in the accompanying drawings, in which—

Figure 1 is a perspective view, and Fig. 2 is a cross-sectional view.

The leading feature of my design consists in a circular hoop 1, the inner and outer faces of which in cross-section are practically parallel, as shown at *a b*, the outer face being

slightly crowned and the edges rounded, as shown at *c*, and a roughened flexible fibrous band *d*, extending from edge to edge of the hoop and covering the face thereof.

These hoops are sold to the trade and are used in conjunction with the outer hoop of the ordinary embroidery-frame.

25

What I claim is—

The design for an embroidery-hoop as herein shown and described.

In testimony whereof I have hereunto set my hand in the presence of two subscribing 30 witnesses.

LEWIS GIBBS.
